UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 13,663, dated February 27, 1883

Application filed January 25, 1883. Term of patent 3½ years.

To all whom it may concern:

Be it known that I, OTTO HEINIGKE, of New Utrecht, in the State of New York, have invented a new and original Design for Carpets, of which the following is a specification.

This invention relates to a new and original design for carpets and similar fabrics; and it consists in the novel grouping and configurations of figures hereinafter more fully described.

The accompanying photograph illustrates a face view of a carpet having my new design.

The ground is filled in with small lobed leaf-like figures without conspicuous grouping, with occasional star-shaped flowers interspersed in sets of threes, and with four larger circular figures occurring irregularly, two—a large and a smaller one—having spiral-like figures arranged circumferentially, and the other two having respectively leaf figures and fret-work similarly arranged, as is clearly shown in the photograph. On this ground lie flower groups,

each consisting of a conspicuous running stem bearing star-shaped flowers and blossoms and terminating in bare twigs. The figures of these flower groups are distinguished in the photograph from the figures of the ground by their outline, which is in each instance darker than their mass.

I claim—

1. The design for a ground for a carpet, consisting of the ground, substantially as shown and described.

2. The design for a carpet, consisting of the running flower groups, substantially as shown and described.

3. The design for a carpet, consisting of the running flower groups and the ground, substantially as shown and described.

OTTO HEINIGKE.
